UNITED STATES PATENT OFFICE.

DANIEL F. LEPLEY, OF CONNELLSVILLE, PENNSYLVANIA.

CAGING APPARATUS.

Application filed August 31, 1922. Serial No. 585,539.

To all whom it may concern:

Be it known that I, DANIEL F. LEPLEY, a citizen of the United States, residing at Connellsville, in the county of Fayette and State of Pennsylvania, have invented a new and useful Caging Apparatus, of which the following is a specification.

This invention relates to mechanism for caging cars and is designed primarily for use in connection with self dumping and overturning cages.

Heretofore it has been the practice to provide front and back horns adapted to move to position in front of the front wheels and back of the rear wheels respectively of a car on the cage, but as the horns have moved simultaneously into or out of engaging positions there have been times when the front wheels of a car being caged have passed the front horns before the rear horns have been released sufficiently to enable the front horns to move to retaining positions. This defect has resulted in trouble.

It is an object of the present invention to so mount and actuate the holding horns that the front horns will be shifted before the rear horns are moved, thus to be brought into position to stop the advancing car positively, the rear horns being brought to holding position at the proper time to prevent the car from rebounding from the cage.

Another object is to provide horns which will be automatically shifted to releasing position when the cage is brought to the point of car delivery, the movement of the horns being simultaneous.

A further object is to provide means whereby the mechanism of the casing apparatus is reset automatically when the car leaves the cage.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings—

Figure 1 is a section through the apparatus constituting the present invention.

Figure 2 is a plan view thereof.

Figure 3 is an end elevation.

Referring to the figures by characters of reference 1 designates the platform portion of a cage provided with rails 2 for receiving cars to be hoisted and dumped. Mounted adjacent each of the rails so as to swing laterally relative thereto, is a front horn 3 and a rear horn 4, these horns being formed with wheel receiving recesses 5 spaced apart a sufficient distance to allow the supporting wheels of a car to stand between the horns and to be held thereby to the rails when the horns are in holding positions. Each horn is supported by a longitudinal shaft 6 provided at one end with a crank arm 6 and the crank arms of the horns 4 are connected by links 7 to a lever 8 mounted, at its center, upon a longitudinal shaft 9 so as to turn therewith. The crank arms 6 of the horns 3 are similarly connected by links and a lever and the levers 8 at the two ends of the cage have arms 10 extending at angles therefrom engaged by a spring pressed rod 11 whereby the horns are held normally pressed against the rails 2 and into position for engaging and retaining the wheels of a car thereon.

One of the shafts 9 is extended toward one end of the platform 1 while the other shaft 9 is extended toward the other end of the platform and extending from the outer end of each of these shafts is a crank 12.

Arranged in the path of the two cranks 12 are tripping fingers 13 each secured to a shaft 14 journaled in suitable bearings 15 and there being a weighted arm 16 for holding the tripping fingers normally in the paths of the cranks 12.

Each shaft 14 is also provided with a releasing finger 17.

Extending downwardly from the platform 1 adjacent each end thereof is a guide 18 and slidably mounted within each guide is a push rod 19 provided, at its outer or free end with a laterally extending finger 20. The inner end of one push rod is connected to the downwardly extending arm 21 of a bell crank 22 fulcrumed on the platform 1. This bell crank has an upper arm 23 normally extending at an incline above and close to one of the rails 2 and between the horns 3 and 4 adjacent said rail. The other rod 19 is connected to one arm 24 of a bell crank 24 the other arm of which engages and supports a cam 25 pivotally

mounted on platform 1 close to the other rail on the platform and to the horn 4 adjacent said rail.

When the cage is raised out of its lower or car delivering position the weighted arms 16 hold the fingers 13 and 17 in upstanding positions, the fingers 13 being in the path of and below the cranks 12 while the fingers 17 are below and in the path of the free ends of the push rods 19. Thus when the platform comes to its lowermost position the rods 19 will be supported on the upper ends of fingers 17 and within the upper portions of the guides 18 while the cranks 15 12 will come down on and be rotated by the fingers 13. It is assumed of course that during this downward movement of the platform a car is positioned with its wheels between horns 3 and 4 and resting on and 20 holding down arm 23 and cam 25. Obviously as soon as the cranks 12 are rotated by coming against the fingers 13 the horns 3 and 4 will be swung laterally thereby and against the action of the spring pressed 25 rod 11. Thus the car held between the horns will be released and when moving off the platform will release the cam 25 and the arm 23. Counterweights 26 and 27 are connected to the bell cranks 22 and 24 respectively so that as soon as these bell cranks are released from the weight of the car they will move upwardly to their normal positions as shown in Figure 1 and thus withdraw the free ends of rods 19 from their 30 positions on the tops of fingers 17. Consequently the free ends of the rods will drop to the lower portions of the guides 18 and in position to thrust against fingers 17. Horns 3 and 4 will be maintained in their 35 lateral or releasing positions as long as the cranks 12 rest on fingers 13. A car entering the cage from the left in Figure 1 will have its front wheels first pass between the horns 4 after which one of the front wheels 40 will engage and depress the cam 25 thus to actuate bell crank 24. This will cause the rod 19 connected to bell crank 24 to shift longitudinally against its finger 17 and rotate finger 13 out of position under crank 45 12. Horns 3 will thus be released and the spring pressed rod 11 throw them inwardly automatically against the sides of the rails 2 and in position to stop the front wheels of the car when brought thereagainst. During 50 the further movement of the car toward the horns 3 and subsequent to the actuation of the cam 25 the other front wheel of the car will come against and depress the arm 23 of bell crank 22. This will cause the rod 55 19 of said bell crank to thrust against its finger 17 and thus withdraw finger 13 from beneath the crank arm 12 resting thereon. Consequently the rear horns 4 will be thrown toward each other by the spring 60 pressed rod 11 controlling them. These 65

horns will first come against the sides of the rear wheels which will slip forward between the horns until said rear horns are free of the wheels whereupon they will continue their inward movement and assume 70 retaining positions back of the rear wheels.

The cage can now move upwardly, carrying its caged load and as soon as it passes above the fingers 13 and 17 the weighted arms 16 will restore said fingers to their 75 normal position so that when the platform is returned to the bottom level or point of starting the operation already described will be repeated.

Obviously by providing mechanism such 80 as described the release of the front horns in advance of the rear horns is assured and there is thus no danger of a car getting past the horns before they are released.

As shown in Figure 1 each front horn 85 can be provided with a resilient bumper or cushion for reducing the shock caused by the abrupt stepping of the loaded car directed onto the cage platform. This bumper can consist of a slide 28 mounted within 90 suitable guides 29 in the horn and held normally against movement by springs 30.

What is claimed is:—

1. The combination with the platform of a cage, and front and rear horns movably supported thereby, of means in the path of the cage for automatically shifting the horns to car releasing positions, and separate independently operated means on the cage for actuation by a car moving in one direction along the cage platform for successively releasing the front horns and the rear horns to car wheel engaging positions. 95

2. The combination with the platform of a cage, and front and rear horns movably connected thereto, of separate independently operated means in the path of the cage platform for shifting the front and rear horns respectively out of car holding positions and holding them against return movement, and separate means operated by a car moving along the platform for successively releasing the front horns and the rear horns from their holding means. 105

3. The combination with the platform of a cage, and front and rear horns movably connected thereto, of separate independently operated means in the path of the cage platform for shifting the front and rear horns respectively out of car holding positions and holding them against return movement, and separate independently operated means actuated by a car moving in one direction along the platform in one direction for successively releasing the front horns and the rear horns from their holding means, and means for automatically shifting the horns to car engaging positions as soon as released. 115

4. The combination with a cage platform and front and rear horns movably mounted 120

- thereon, of separate tripping means in the path of the platform, separate means carried by the platform and movable against the respective tripping means for shifting the front and rear horns respectively out of car engaging positions, and separate means on the platform and separately operated by a car moving in one direction upon the platform, for independently shifting the respective tripping means to release the horn shifting means therefrom, and means for automatically returning the horns to car engaging positions when released.
5. The combination with a cage platform and front and rear horns movably mounted thereon, of separate tripping means in the path of the platform, means for holding the tripping means normally in operative positions, separate means carried by the platform and cooperating with the respective tripping means when in normal position for shifting the front and rear horns respectively out of active positions, and separate means operated by a car moving onto the platform for successively moving the tripping means out of normal positions and successively releasing the horns, and means for automatically returning the released horns to operative positions.
10. The combination with a cage platform and front and rear horns movably connected thereto, of yieldingly held tripping devices in the path of the platform, separate means movable with the platform for engagement with the respective tripping devices to shift the horns out of normal positions, means for returning the horns automatically to normal positions when released, separate depressible members on the platform for engagement by wheels of a car on the platform, and separate means operated by the respective depressible members for shifting the tripping devices to release the horns.
15. The combination with a cage platform and yieldingly held horns movably mounted thereon and normally positioned for engagement with a car on the platform, of separate means for automatically shifting the respective horns out of their normal position when the platform is brought to car releasing position, and means operated successively by a car moving along the platform, for successively releasing the shifted front and rear horns.
20. The combination with a cage platform and horns movably mounted thereon for engagement with a car on the platform, of a tripping member, means on the platform and movable against the tripping member to shift the horns to car releasing positions, a push rod movable with the platform and movable against and adapted to be shifted out of normal position by the tripping member when the platform is brought to car releasing position means operating during the delivery of a car from the platform for automatically setting the push rod in position to thrust against the tripping member, and means operated by the movement of a car onto the platform for actuating the push rod to shift the tripping member out of operative relation with the horns and release the horns to car engaging positions.
25. The combination with a cage platform and yieldingly held horns movably mounted thereon and normally positioned for engagement with a car on the platform, of separate, independently operated means for automatically shifting the respective horns out of their normal position when the platform is brought to car releasing position, independently operated means actuated by a car moving onto the platform for releasing the respective shifted horns, means released by the delivery of a car from the platform for releasing the shifted horns, and means released by the delivery of a car from the platform for resetting said horn releasing means.
30. In testimony that I claim the foregoing as my own, I have hereto affixed my signature in the presence of two witnesses.
